(57) **CLAIM**

The ornamental design for a auxiliary wheel installation bracket as shown and described.

DESCRIPTION

FIG. 1 is a front perspective view of a auxiliary wheel installation bracket showing my new design.

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof;

FIG. 9 is an enlarged detail view taken from portion 9 of FIG. 1;

FIG. 10 is an enlarged detail view taken from portion 10 of FIG. 1;

FIG. 11 is an enlarged detail view taken from portion 11 of FIG. 1; and,

FIG. 12 is an enlarged detail view taken from portion 11 of FIG. 6.

The broken lines depict the boundaries of the enlargement areas and lead lines, which form no part of the claimed design.
